PLOWING-MACHINE.

1,124,558.

Specification of Letters Patent.

Patented Jan. 12, 1915.

Application filed October 3, 1911. Serial No. 652,584.

To all whom it may concern:

Be it known that we, JOHN K. UNDERWOOD, JOHN B. UNDERWOOD, and GEORGE T. UNDERWOOD, citizens of the United States, 5 residing at Syracuse, in the county of Hamilton and State of Kansas, have invented a new and useful Plowing-Machine, of which the following is a specification.

Our invention relates to a disk plowing machine equipped with motive power and obtaining traction by a traction wheel which follows in the furrow made by the last disk and aims to provide a plowing machine which at the same time will obtain sufficient 10 traction to suffice for its efficient operation and providing means for obtaining the ready adjustment of the machine to a suitable tractor for other purposes. Upon a careful consideration of the drawings wherein is 15 disclosed the preferred form of my machine, it will be recognized that this is very simple and consists of but a few parts whereby the same may be manufactured and placed upon the market at a minimum cost. In devices 20 of this nature, weight has to be given a considerable consideration in view of the fact that this is essential for obtaining sufficient traction. While our invention as disclosed herein appears to be very light, it is 25 thought that the combined weight of the different parts and also of a motor will give the required weight to the disks and to the rear traction wheel and thereby assure the efficient working of the machine.

30 By devising a machine consisting of but a few parts, we have attained several objects, namely, a machine wherein the different parts can be readily removed and replaced by others by the operator; one wherein 35 in all the parts can be quickly cleaned without dismembering the entire machine. By obviating the numerous superfluous parts the cost of manufacture is greatly reduced and by the provision of a solid framework 40 and only a few parts carried thereby, the danger of the machine or the parts thereof getting out of order is obviated.

Broadly our invention consists of a body portion which will be hereinafter termed as 45 a supporting structure which is supported at its forward end by a pair of comparatively small wheels and its rear end by a single traction wheel, the traction wheel being rotated through the medium of suitable 50 gearing connected to a motor carried upon

the body portion. A rod carrying a plurality of disks is carried by the machine and disposed at a substantially obtuse angle thereto so that when the machine is in operation the traction wheel will follow in the furrow formed by the last disk. By the provision of the number of disks, it is apparent 60 that while the ground is plowed it is also pulverized, thereby obviating the use of other machines for this purpose. 65

Means including suitable common mechanism have been devised for purpose of regulating and adjusting the disks, that is, if a deep furrow is to be made the mechanism can be operated to operate the disks as set 70 forth, however, if only a light furrow is to be opened, the disks can be drawn up to a considerable extent.

Taking the above mentioned objects in view and carefully considering them in view 75 of the foregoing, it will be recognized that the machine which we have provided overcomes the numerous difficulties which have heretofore existed and provides a simple, efficient and inexpensive machine which can 80 be easily operated and transported from place to place.

With the above and other objects in view, our invention relates to such details of construction and in the arrangement and combination of the several parts as will be hereinafter fully described and specifically pointed out in the appended claims.

In describing our invention in detail, reference will be had to the accompanying 90 drawings wherein like characters denote like or corresponding parts throughout the several parts, and in which:

Figure 1 is a plan view of our invention. Fig. 2 is a side elevation thereof, and Fig. 95 3 is a detail view. Fig. 4 is a fragmentary rear end elevational view of our invention showing to advantage the manner of supporting the frame from the rear axle.

In the accompanying drawings wherein 100 is illustrated the preferred form of our invention, the numeral 10 designates the body portion or supporting structure which is carried at its forward end upon braces 11, the latter having engagement with an axle 105 12 as shown at 13 with the body portion as shown at 14. This axle is then in turn supported through the medium of the wheels 15. The body portion above referred to and as will be appreciated upon reference to the 110

drawings, is substantially oblong in shape and it is disposed nearer one of the wheels 15 than the other, this being for the purpose that will be hereinafter set forth. The rear 5 end of the body portion carries a brace 16 which is substantially U shaped as shown at 17, the latter having engagement with an axle 19 carrying a traction wheel 20. For the purpose of yieldingly supporting the 0 body portion upon the axle 19, we have provided the coil springs 21, which are disposed about the connecting bolts 19' on the enlargement 50 and the sleeve 68 of the brace rod 66 and serve to hold the outer ends of 15 the U-shaped brace 17 in spaced relation to the axle 19. It will be obvious that the respective ends of the spring 21, bear against the points of securement of the bolts and the outer ends of the U-shaped brace 17, which 20 brace is held in place with the spring by means of the nuts 21', screw-threaded on the outer ends of the bolts 19'. An engine 22 carrying a fly wheel 23 at one side thereof is disposed upon the body portion and secured in place by any suitable means. A cross piece 24 is also carried by the body portion and disposed adjacent the engine, it having a pair of parallel spaced apart arms 25 and 26 respectively projecting therefrom, the latter arm having the crank shaft of the engine as shown at 27 journaled therethrough and supported through the medium of a bushing 28. The crank shaft extends as above set forth through the arm 25 30 and is supported upon the arm 25 through the medium of the cup shaped member 29, the latter serving as a socket. The gear wheel and pinion 30 and 31 respectively are fixedly carried upon a sleeve 31', which sleeve is slidably but non-rotatively carried upon the crank shaft, the pinion being in engagement with another gear wheel 32 on the sub-shaft 33 as is shown. The sub-shaft 33 is journaled through the arms 25 and 26 35 and carries aside from the gear wheel 32 pinions 34 and 35. Another shaft 36 is journaled through the body portion and extends through the arms 25 and 26, it carrying a gear wheel 37 intermediate its end 45 and carries aside from the gear wheel 32 pinions 34 and 35. Another shaft 36 is journaled through the body portion and extends through the arms 25 and 26, it carrying a gear wheel 37 intermediate its end 50 which meshes with the pinion 35 as is shown, for purpose of transmitting motion to the shaft 36. A sprocket wheel is carried upon the shaft 36 and has in engagement therewith a sprocket chain 38, the latter also engaging a sprocket wheel 39 upon the axle 19, for the purpose of rotating the axle and the traction wheel 20 carried thereby and thereby propelling the machine. Another sprocket wheel is also carried upon 55 the shaft 36 and receives a second sprocket chain 40, this sprocket chain engaging a sprocket chain 41 on the axle 19 so as to serve as an auxiliary propelling wheel and thereby insuring the efficient operation of 60 the device.

It is now apparent that when the engine is started motion will be transmitted from the crank shaft to the subshaft 33, from the pinion 35 to the gear wheel 37 on the shaft 36. Through the shaft 36, the motion is 70 transmitted at each end to the axle 19 through the medium of the sprocket chains 38 and 40 with the coöperation of the sprocket wheels 39 and 41. By this arrangement it is apparent that the propelling means of our invention is very simple and that each of the parts is disposed to be easily adjusted by the operator so that he can replace different worn parts by new ones 75 if he so desires.

A rod 42 is provided which carries thereon a plurality of concavo-convex disks 43, the latter being fast upon the rod. The forward end of the rod 42 is supported upon the axle 12 through the medium of an arm 44, which has engagement with the rod through the medium of the nut and bolt arrangement 45, and which is provided at its front end with an opening for the reception of a lug 46 the latter being carried 80 upon an adjustable sleeve 47 disposed about the axle 12. The adjustability of the sleeve can be had through the manipulation of the set screw 48 as is clearly obvious. By the provision of the adjustable sleeve, it is apparent that the position of the rod and disks can be adjusted to vary the width of the furrow opened by the different disks. The rear end of the rod 42 is supported upon the axle 19 through the medium of a standard 85 49, the latter having engagement with the rod as is clearly shown and being provided with an enlargement 50 at its rear end which is in turn provided with an opening 51 for the reception of the axle. The standard 49 also carries intermediate its end a pair of oppositely extending brackets 52 which support the friction rollers 53 which are in engagement with a sprocket chain 54 operating about a wheel 55 on the rod 42 and extending for engagement with a companion wheel 56 carried fast with the sprocket wheel 39 on the shaft 19. By this arrangement, it is apparent that as the traction wheel 20 is operated that motion will also be transmitted to the disks whereby they will be revolved in the well known manner.

As the arm 44, is pivoted to the axle 12, and as the standard 49, and the brace rod 56 are loosely connected to the shaft 19, we have provided a simple means for raising and lowering the disk rod 42, which in this instance consists essentially of cables 58 and 58', the former being secured to the arm by means of a link 57, operates from a friction roller 59, carried upon the extending brace rod 60, and secured thereto as shown at 61. The cable 58, now extends across the entire body of the machine and about a friction roller 62, secured to the far sides of the body 125 110 115 120 125 130

portion as is shown. The cable 58 is secured to the standard 49 by means of a link 57 and operates from a roller 59 secured to the side of the body portion 10, as shown at 61'. A vertical staff 63, carrying a hand wheel 64 at its upper end is positioned upon the body portion and held in place by the pawl and ratchet arrangement 65, the staff receiving the cables 58 and 58' whereby when the latter are wound thereon, the disks may be moved into a raised position and consequently out of engagement with the ground.

For purpose of more securely supporting the rear end of the rod 42 in connection with the device we have provided a peculiar shaped brace rod 66 which has one end secured to a block 67 carried by the standard 49, while the other end is pivoted to a portion of the axle 19 as shown by a sleeve 68 on the rear end of the rod 66.

For purpose of varying the speed of the drive and consequently facilitating the operation of the device, we have fulcrumed, intermediate its ends, upon the cross-piece 24, a lever 69, pivotally connected at one end by a pin and slot arrangement 69' to the collar 70', loosely mounted upon the sleeve 31' between the gear 30 and the pinion 31, and which lever and sleeve operate in conjunction with the pinion 31 and gear wheel 30 so as to, at certain times, establish communication directly between the same and the gear and pinion on the shaft 33, however, they may be thrown out of engagement with each other at certain times when the machine is desired to be brought to a standstill. By the provision of the arrangement above referred to, it will be appreciated as above set forth that the efficiency and operativeness of our invention has been greatly added to. For instance, if the machine is traveling at a certain rate of speed and the dirt clogs between the wheels or they strike a stone or some hard structure, the operator can, upon the manipulation of the hand lever 70, disengage the pinion and gear wheel on the shaft 23 from the pinion and gear wheel on the shaft 33 through the medium of the cable 71, which operates on the friction roller 71' on one side of the body portion and has its respective ends connected to the ends of the hand lever 69 on the transverse bar 24. It is obvious that the gears may be returned to their normal position by a spring (not shown), mounted in any suitable manner on the shaft 23.

The lever above referred to and designated by the numeral 70 is pivoted as shown at 72 upon a segmental rack 73, the latter being engaged by a pawl 74 carried upon the pivoted hand wheel 75, the latter being of the usual type. By the provision of the pawl and ratchet arrangement in connection with this device, it is apparent that the lever

may be held in different positions according to the desire of the operator.

We have devised a suitable means whereby our machine may be guided during its travel over the ground which means is inexpensive to manufacture and easily detached or attached to or from the machine when occasion requires. This guiding mechanism consists of a substantially vertically disposed staff 76 which has positioned thereon and at its upper end a hand wheel 77 whereby the rotation of the staff may be effected. The lower end of the staff as referred to has positioned thereon a worm gear 78 which normally meshes with a worm gear 79 which is carried upon the longitudinally extending rod 80, the latter having its forward end journaled into the supporting structure as shown at 81. Provided upon the rod 80 and preferably intermediate its ends is a block 82 which has connection at 83 to a finger 84, the latter being pivotally secured to a transversely extending member 85 as is clearly illustrated. The member 85 mentioned extends transversely to the body portion of the device and is pivotally secured at its extremities as shown at 86 to a pair of links 87, the latter being in turn fast upon the pivoted sections 88 of the axle 12 as shown at 89. By this arrangement, it is readily apparent that as soon as the hand wheel 77 is rotated, motion will be communicated through the pair of worm gears to the rod 80 and wheels, and the wheels of the vehicle thereby moving the latter so as to guide the machine during its travel over the ground.

While we have illustrated the ordinary form of machine in the preferred form of our invention, it is to be appreciated that other forms of propelling means may be devised and provided such as gas engines, electric machines or any suitable device.

From the foregoing it is thought that the advantages and novel features of our invention will be readily comprehended.

We desire it to be understood that we may make slight changes in the construction and in the arrangement and combination of the several parts, provided, however, such changes fall within the scope of the subjoined claims.

Having thus fully described our invention, what we claim as new and desire to secure by Letters Patent, is:—

1. In a device of the character described, a body portion, means for supporting the front and rear ends of said body portion, a rod, earth-engaging elements carried by said rod, means for supporting one end of said rod from the rear body portion supporting means, and means for adjustably connecting the other end of said rod with the forward end of said body portion supporting means.
2. In a device of the character described, a

4. In a device of the character described, a body portion, means for supporting the front and rear ends of said body portion, a rod, earth engaging elements carried by said rod, and means for movably supporting one end of said rod from the rear of said body portion supporting means, means for adjustably connecting and supporting the other end of said rod with the other of said body portion supporting means, and means connected to the respective ends of said rod and said body portion for raising said earth-engaging elements out of engagement with the earth.
3. In a device of the character described, a body portion, means for supporting the front and rear ends of said body portion, a rod, a plurality of disks rigidly mounted upon said rod, a standard, one end of which is connected to the rear of said supporting means, an arm, one end of which is connected to the opposite end of said rod and the opposite end of said arm being adjustably connected to the forward of said supporting means.
4. In a device of the character described, a body portion, means for supporting the front and rear ends of said body portion, a rod, a plurality of disks rigidly mounted upon said rod, a standard, one end of which is connected to the rear of said supporting means, an arm, one end of which is connected to the opposite end of said rod and the opposite end of said arm being adjustably connected to the forward of said supporting means, and means connected to said standard and said arm for simultaneously raising the respective ends of said rod to bring said disks out of engagement with the ground.
5. In a device of the character described, a body portion, means for supporting the front and rear ends of said body portion, a rod, a plurality of disks rigidly carried by said rod, a standard pivotally connected to the rear of said supporting means, an arm slidably and pivotally connected to the forward of said supporting means, said rod being rotatably mounted in the free ends of said standard and said arm, and flexible means connected to said standard and said arm for simultaneously raising the respective ends of said rod to bring said disks out of engagement with the ground.
6. In a device of the character described, a body portion substantially elongated in form, an axle supporting the forward end of said body portion, an axle supporting the rear end of said body portion, a pair of wheels supporting said first mentioned axle, one of said wheels being disposed comparatively farther from said body portion than the other of said wheels, a single traction wheel supported by the second mentioned axle, said last mentioned axle being yieldingly supported upon said body portion, a rod extending diagonally from the longitudinal axis of said body portion, an arm connecting one end of said rod and said first mentioned axle, a standard connecting one end of said rod and said last mentioned axle, a plurality of disks carried by said rod and means for rotating said rod as and for the purpose set forth and described.
7. A device of the character described comprising a body portion, axles journaled through the respective ends of said body portion, supporting wheels rotatably mounted upon the free ends of the forward of said axles, a traction wheel rigidly mounted up on the rear axle, an engine carried by said body portion, means connecting said engine and said rear supporting axle for imparting movement to the body portion, a rod, a plurality of disks rigidly carried by said rod, a standard pivotally connected to the rear axle, an arm slidably and pivotally connected to the forward axle, said rod being rotatably mounted in the free ends of said standard and said arm, means connecting the rear axle and the rod for imparting a rotary movement to the rod, cables connecting said standard and said arm and said body portion, and means for operating said cables for simultaneously raising the respective ends of said rod to bring said disks out of engagement with the ground.
